UNITED STATES PATENT OFFICE.

JOHN VISHLOFF, OF LUNDBRECK, ALBERTA, CANADA.

WOOL-COMBING IMPLEMENT.

Application filed September 15, 1922. Serial No. 588,423.

To all whom it may concern:

Be it known that I, JOHN VISHLOFF, a citizen of Russia, residing at Lundbreck, in the Province of Alberta and Dominion of Canada, have invented certain new and useful Improvements in Wool-Combing Implements, of which the following is a specification.

This invention relates to a wool combing implement intended more particularly for use in mixing up various grades of wool for use in paddings or fillings.

The invention has for an object to provide a novel and improved wool combing implement which will be simple and inexpensive to construct, and efficient in operation.

For further comprehension of the invention, and of the objects and advantages thereof, references will be had to the following description and accompanying drawings, and to the appended claims in which the various novel features of the invention are more particularly set forth.

Fig. 1 of the drawings is a detail perspective view of my improved wool combing implement.

Fig. 2 is a longitudinal vertical sectional view of the fixed comb element.

Fig. 3 is a plan view of the other combing element.

Fig. 4 is a longitudinal vertical sectional view thereof.

My improved wool combing implement comprises briefly, a pair of members each provided with comb teeth, one of said members being adapted for fixing on a bench, table or the like, while the other is held in the hand of and manipulated by, the workman.

In constructing my improved wool combing implement I provide a pair of flat plate-like backing or body members 10 and 20 respectively, the member 10 being adapted to be secured to the bench or table, as by a screw 12 passed through a suitable aperture therein and screwed into the said bench or table. The other member 20, is adapted to be held in the hand of the workman and is provided with an integral handle extension 13.

At the end opposite the handle extension 13 the body 20 presents a straight transverse edge while the body element 10 has a

like edge on the end thereof nearest the edge of the bench or table on which it may be mounted.

Projecting substantially vertically from these edges are the comb teeth 15 and 28 respectively. The teeth 15 on the member 10 project from a narrow backing element such as 17 which engages in a chamfered recess in the edge of the said member, and which may be held in place by a strip 18 secured in place by screws such as 19. The teeth 28 on the member 20 are adjustable so as to vary both the effective length thereof and the angle of projection from the said member.

To this end the body member 20 is provided and has fixed therein a transverse rod 21 on which is loosely mounted a frame 22 having a pair of forwardly projecting lugs 23 having pivotal engagement as at 24 with a second pair of lugs 25 projecting rearwardly from a transverse bar 26 in which is fixed the backing element 27 of a comb 28. Pivoted at one end to the bar 26 as at 29, and extending obliquely backward, are a pair of links which are pivotally connected at their other ends as at 30 to the body 20. These links are of variable length comprising the right and left hand threaded elements 32 and 33 engaged with a turnbuckle 34, the latter having a pair of holes 35 therein to receive a turning rod.

Formed on the frame 22, concentric to the rod 21, is a worm segment 37 engaged by a worm pinion 38 suitably journaled in the body 20, the various parts above described being accommodated in a recess 39 in the latter. The worm pinion 38 has fixed to one of the trunnions thereof a wing head 40 whereby it may be turned, this wing head being accommodated in a smaller recess 41 in the member 20, said recess being normally covered by a removable plate 42.

As will be apparent, by suitable manipulation of the turnbuckles 34 and the head 40, the teeth 28 may either have their angle with respect to the comb body 20 varied, or their effective length varied, or a combination of both adjustments may be effected.

In use the wool to be mixed is placed on the fixed member 10 and is combed or pulled through the teeth 15 thereon by the teeth 28 on the part 20.

Having thus described my invention

what I claim as new and desire to protect by Letters Patent of the United States is as follows:—

1. A comb comprising a body element, 5 teeth extending at an angle thereto, a hinged bar on which said teeth are fixed, and worm and pinion means for swinging said bar, to vary the relation of the teeth to the said body element.
- 10 2. A comb comprising a body element, a frame pivoted therein, means for adjusting said frame on its pivoted axis, a tooth carrying element pivoted to said frame, and a longitudinally adjustable link connected at one end to said body element, and at its op-

posite end to said tooth carrying element at a point removed from the point of connection of said tooth carrying element to said frame.

- 15 3. A comb comprising a body element, a frame pivoted therein, a bar pivoted to said frame on a parallel axis, teeth fixed to said bar, a longitudinally adjustable link connecting said bar to said body element, a worm segment on said frame, and a worm 20 pinion engaging said worm segment.

In testimony whereof I have affixed my signature.

JOHN VISHLOFF.
